UNITED STATES PATENT OFFICE.

EMANUEL FOERSTER, OF NEW YORK, N. Y.

MOLD FOR CASTING TEETH FOR DIAMOND-SAWS.

SPECIFICATION forming part of Letters Patent No. 340,204, dated April 20, 1886.

Application filed August 22, 1885. Serial No. 175,055. (No model.)

To all whom it may concern:

Be it known that I, EMANUEL FOERSTER, of the city, county, and State of New York, have invented certain new and useful Improvements 5 in Molds for Casting Teeth for Diamond-Saws, of which the following is a specification.

This invention has reference to an improved mold for casting teeth for diamond-saws, the mold being specially designed to adjust and 10 hold the diamonds, so as to secure the exact position of the same for casting the metal tooth around the same.

In the accompanying drawings, Figure 1 represents a side elevation of my improved mold 15 for casting diamond-saw-teeth. Fig. 2 is a top view; Fig. 3, an end elevation; Fig. 4, a vertical transverse section on line $x-x$, Fig. 2; Fig. 5, a horizontal section of the same on line $y-y$, Fig. 1; and Fig. 6 are end views of saw-teeth, showing 20 different ways of setting the diamonds.

Similar letters of reference indicate corresponding parts.

Referring to the drawings, A A represent the side walls of my improved mold for casting 25 the teeth of diamond-saws, which are respectively provided with a gate, a, for the molten metal, and a vent-hole, a', for the escape of the air. To the side walls, A A, is attached, by screws b b, a bottom plate, B. The side walls, 30 A A, are provided with recesses at their middle parts, where the body of the saw-tooth is to be cast. Side plates, d d, extend longitudinally of the mold outside the side walls, A A, and serve to cover the central apertures or recesses 35 therein. These side plates are held in place by bolts C C, which pass through them and through the side walls, A A. These side plates, d d, may, if desired, be cast integral with the walls A A. In said recesses are arranged a 40 number of laterally-movable cheeks, e e, which are adjusted from the outside by screws e', that pass through threaded holes in the plates d and engage by their inner pin-shaped ends socket-holes of the cheeks e. The faces of the cheeks 45 e are either smooth or provided alternately with forward-projecting pins e². The smooth cheeks e e are used for setting diamonds of larger size, which project at both sides of the saw-tooth, while the cheeks with pins e² serve 50 for setting diamonds of smaller size.

For setting the diamonds into the mold pre-

paratory to casting the body of the tooth around the same, the bottom plate is removed and the diamonds clamped between two opposite cheeks e e, or between one of the cheeks e and 55 the pin e² of the opposite cheek, by screwing up the set-screws e' e'. According to the size of the diamonds, they are set either into line or in such a position that they project alternately at opposite sides of the body of the tooth, as 60 shown in Fig. 6. The bottom plate, B, is then replaced and the diamonds set thereby in line. The metal is then cast in the usual manner around the diamonds, and the tooth afterward 65 inserted into the saw-blade.

The top of the mold is covered by a plate, D, which lies between the side walls, A A, in a plane above the recessed portion thereof. The mold is closed at its ends by end pieces, E, which are fitted between the walls A A and extend 70 from the bottom B to the top plate, D. These end pieces are preferably V-shaped in cross-section, whereby grooves are formed in the saw-tooth for the insertion thereof in the blade of the saw; or the end pieces may be reversed, so 75 as to taper the edge of the saw-tooth and adapt it to fit the groove in the saw-blade.

By casting the body around the diamonds and alternating the position of the diamonds, diamonds of very small size can be advantageously used, whereby the expense of diamond-saws is considerably diminished.

The arrangement of the cheeks with independent set-screws which bear on the diamonds facilitates their accurate adjustment without 85 shifting them axially, which is the case in molds in which the set-screws are applied directly to the diamonds. The metal body is cast nearly flush with the diamonds, the points of which project slightly beyond the metal. 90

As the diamonds become worn, they are reset again from time to time by casting a new body of metal around them, whereby they can be used until entirely worn out.

Any shape of diamond can be used, as the 95 cheeks bind readily thereon and hold them accurately and reliably in position.

Having thus described my invention, I claim as new and desire to secure by Letters Patent—

1. The combination, in a mold for casting 100 teeth for diamond-saws, of recessed side walls, side plates, a bottom plate, and laterally-ad-

justable cheeks within the recesses of the side walls, said cheeks having their inner faces flush with the inner faces of the side walls when in operative position, whereby they constitute parts of the mold surface in line with said walls, and set-screws threaded into the side plates and engaging said cheeks, substantially as described.

2. The combination of a mold-body having recessed side walls, side plates, and a bottom plate, of laterally-adjustable cheeks provided alternately with projecting pins and set-screws threaded into the side plates and engaging sockets of said cheeks, substantially as set forth.

3. The combination of the recessed supporting side walls, A A, covering side plates, d d, bottom plate, B, cheeks e e, set into the recesses of the side walls and having socket-holes, and set-screws e' e', threaded into the side plates and having smooth ends for engaging the socket-holes of the cheeks, substantially as described.

In testimony that I claim the foregoing as my invention I have signed my name in the presence of two subscribing witnesses.

EMANUEL FOERSTER.
